United States Patent Office.

JACOB S. DETRICK, OF SAN FRANCISCO, CALIFORNIA, ASSIGNOR TO HIMSELF AND WILLIAM R. ECKERT, OF SAME PLACE.

Letters Patent No. 80,612, dated August 4, 1868.

IMPROVEMENT IN COUNTING-REGISTERS.

The Schedule referred to in these Letters Patent and making part of the same.

TO ALL WHOM IT MAY CONCERN:

Be it known that I, JACOB S. DETRICK, of the city and county of San Francisco, and State of California, have invented a new and improved Pocket-Counter; and I do hereby declare that the following is a full, clear, and exact description of the construction and operation of the same, reference being had to the annexed drawings, making a part of this specification, in which—

Figure 1 is a side view.

Figure 2 is a section through the line $z z$ of fig. 3.

Figure 3 is a section through the line $y y$ of fig. 1.

The object of this invention is to provide a neat and convenient pocket-instrument, by which the velocity of shafting, &c., can be accurately determined.

In the drawings, A is a circular plate, having a rim, B, and forming the back and edge of the instrument, and also coming down upon the face of it, around its periphery, so as to form an annular rim, C.

D is the central portion of the face of the instrument.

E is a spur-wheel, revolving on a spindle or journal, F, at the centre of the instrument, and provided with one hundred and one cogs, *e e*.

I is another spur-wheel, of the same size as the wheel E, provided with one hundred cogs, *i i*, and revolving on the same shaft or spindle, in front of the wheel E. It is also provided with a projecting ring, M, which comes out even with the face of the instrument, between the rim C and the central portion, D, and is graduated from 0 to 100.

The central part, D, of the face is connected with the wheel E by being attached to the shaft F, so as to revolve with the shaft and the wheel E. The wheel I revolves loosely on the shaft, or on a collar or flange of the wheel E surrounding the shaft. Either of the wheels, E I, may have the one hundred cogs, the other having one hundred and one. The only difference that will result will be that the revolutions will be counted to the right from a fixed point on the ring M, in one instance, and to the left in the other.

In connection with these parts I employ a lever, G, pivoted to the rim B at *b*, and provided with a socket, *m*, to receive and hold the connecting-spindle.

J is a detachable connecting-spindle, having a sharp-pointed head, *j*, or, in lieu of it, a flat rubber or gutta-percha head, and having also a worm-screw, *n*, of such a pitch that one revolution of it will advance the wheels E and I each one cog.

The outer end of the socket *m* is enlarged, to receive the screw *n*, and its lower side is cut away, to allow the screw to gear with the cogs *e* and *i*. A niche or opening is cut in the rim B, at that point into which the screw drops, and which prevents the connecting-spindle from escaping from its socket *m* when the lever G is in the position shown in fig. 1 or 2.

By depressing the end, *g*, of the lever, the screw *n* will be thrown up, so that it will ungear with the cogs of the two wheels, and can readily be removed. By pressing upward with the thumb or finger against the end, *g*, the screw will be held firmly in gear with the wheels.

The operation of this instrument is as follows:

The end, *g*, is depressed, and the connecting-spindle placed in its socket, and brought down into gear with the two wheels E and I, they having previously been set so that the 100 on the ring M is at the arrow *a*, on the rim C, and at the arrow *a'* on the central part, D, of the face. The parts being held in this position by the thumb or finger, the head *j* is applied to the centre of the shaft whose velocity is to be ascertained, and held so firmly against it that the motion of the shaft will be communicated to the connecting-spindle. One hundred revolutions of the latter will then turn the wheels E and I through the space occupied by one hundred cogs on each, giving one wheel a full revolution and the other a whole revolution minus one cog. The arrow *a'*, on the plate D, will then be distant from 100 on the ring M just one degree, indicating one hundred revolutions of the

shaft. Every subsequent one hundred revolutions of the shaft will separate the arrow from 100 one degree farther, until it passes through the whole one hundred degrees, indicating ten thousand revolutions of the shaft. If it is desired that the arrow a' shall move forward, or to the right, from 100 on the ring, the wheel E must have one hundred cogs, the other having one hundred and one.

Having thus described my invention, what I claim as new, and desire to secure by Letters Patent, is—

The combination of the lever G, or its equivalent, with the detachable spindle J and the wheels E I, when the parts are constructed and arranged so as to operate together, substantially in the manner and for the purposes indicated.

To the above specification of my invention I have signed my hand, this 16th day of March, 1868.

JACOB S. DETRICK.
